UNITED STATES PATENT OFFICE.

VICTOR L. COVEY, OF TELL CITY, INDIANA, AND TONA COVEY, OF LOUISVILLE, KENTUCKY.

CANE STRIPPER.

1,424,989.

Specification of Letters Patent. Patented Aug. 8, 1922.

Application filed March 9, 1921. Serial No. 451,083.

To all whom it may concern:

Be it known that we, VICTOR L. COVEY and TONA COVEY, citizens of the United States, residing at Tell City, in the county of Perry and State of Indiana, and Louisville, in the county of Jefferson and State of Kentucky, respectively, have invented certain new and useful Improvements in Cane Strippers, of which the following is a specification.

Our invention seeks to provide means which may be readily connected with a grinding mill and whereby the leaves of sorghum or sugar cane may be stripped from the stalks and the stripping and grinding performed in one single continuous operation so that time and labor will be saved. The invention also seeks to provide a mechanism for the stated purpose which will effectually guide the stalks to the stripper blades and hold them in such position that the leaves will be effectually engaged and stripped from the stalks, a still further object of the invention being to provide means whereby the stripper blades will be prevented from injuring the operator or attendant. A still further object of the invention is to provide means whereby the leaves stripped from the stalks will be prevented from accumulating and will be driven off in such a manner that they may be easily collected and utilized as fodder or in other ways. The invention further seeks to provide an apparatus having the stated characteristics which will be simple in construction, compact in arrangement and strong and durable.

The invention is illustrated in the accompanying drawings and will be herein-after fully described, the novel features being subsequently particularly pointed out in the appended claims.

In the drawings—

Figure 1 is a side elevation of a machine embodying our improvements;

Fig. 2 is a similar view showing the opposite side of the machine;

Fig. 3 is a longitudinal section;

Fig. 4 is a plan view.

In carrying out our invention, we employ sills 1 which are shown as secured to supporting posts or standards 2. Side plates 3 are secured to the sills so that the mechanism will be enclosed and injury to the working parts or to the operator will be thereby avoided. Short standards 4 are

erected upon the sills 1 and beams 5 are carried by the upper ends of the said standards and the posts 2, as shown, extension plates 5' being secured to the beams and adapted to be bolted to the frame of a grinding mill. The top plate 6 is secured upon the beams 5 and cross bars or braces 7 extend between the posts and the sills to provide the requisite rigidity and strength. The top plate 6 is provided with an opening 8 through which the feeding rollers 9 and 10 may engage the stalks and in rear of the said opening a plurality of longitudinal slots 11 is provided in the top plate, as shown. The machine is intended to be placed in juxtaposition to the grinding mill and the stalks are fed over the plate 6 and pass from the said plate directly between the grinding rollers, indicated at 12 in Fig. 1. The lower feeding roller 10 is carried by a shaft 13 which is mounted in suitable bearings upon the sides of the frame and is equipped at one end with a sprocket gear 14 around which and a sprocket pinion 15 on the stripper shaft 16 is trained a sprocket chain 17. The sprocket pinion 15 should be wide enough to accommodate two sprocket chains and a chain 18 is trained around the same and also around a sprocket 19 on the shaft 20 carrying the upper feed roller. As shown in Fig. 1, the chain 18 will be long enough to be somewhat slack in one of its runs so that it will accommodate the relative vertical movement of the upper feed roller. The said upper feed roller is supported by arms or levers 21 having suitable bearings at their rear ends to receive the ends of the shaft 20 and having their front ends pivoted to the top plate 6, as indicated at 22. A spring 23 is attached to each arm 21 and extends downwardly therefrom through an opening 24 in the top plate and is secured at its lower end to the supporting frame whereby the arms are normally held toward the top plate so that the feed roller will exert the desired pressure upon the stalks to effect the feeding operation. The springs, however, will permit the upper feed roller to yield to the stalks according to the diameters thereof so that there will be no premature crushing of the stalks by the rollers, but at the same time a positive engagement with the rollers will be effected and the cane fed to the strippers. It will be noted that both feed rollers are positively driven so that neither roller exerts a drag.

on the cane and, therefore, the cane will be fed smoothly and evenly to the strippers and the grinding mill.

Immediately in front of the feeding rollers, we provide upon the top plate a transverse series of pins 25 which correspond in number to the slots 11 and are respectively alined with said slots. These pins serve to space the stalks as they are fed to the feeding rollers and guide them to the spaces between the slots 11 so that the stalks cannot assume positions oblique to the table or top plate but will be fed over the table parallel with and between the said slots.

15 The stripper shaft 16 is journaled in suitable bearings upon the frame below the slots 11 and the stripper is carried by said shaft. The stripper comprises a drum, roller, or cylinder 26 and a plurality of knives or blades 27 secured to and radiating from the said drum or cylinder. The blades or knives are of such length that as the stripper is rotated the blades will successively pass up through the respective slots 11 and act upon 20 the cane so as to strip the leaves from the stalks. There should be at least four blades in the vertical plane of each slot so that there will be no time in the operation of the machine when there will not be a portion of 25 some blade projecting through each slot. The blades will, therefore, serve not only to remove the leaves from the stalks but will also serve to prevent the stalks slipping sideways and will guide them in longitudinal parallel planes over the table top into 30 the grinding mill. Secured upon the table top over the stripper is a hood 28 which will positively prevent the hands or clothing of 35 the operator coming into contact with the 40 blades and injury to the operator is thereby avoided. The said hood decreases in height toward its rear end, as indicated at 29, and the rear portion of the hood, therefore, serves as a positive guide to present the 45 stalks to the grinding rollers in a horizontal plane and without bunching.

The stripper is also enclosed by a casing 30 and upon the end of the stripper shaft, remote from the sprocket pinion 15, we secure a sprocket 31 around which is trained a chain 32 which is also trained around a pinion 33 on the fan shaft 34. At the opposite end of the fan shaft is a pulley 35 to which power is applied from the grinding mill through a belt 36, as will be readily understood. The fan shaft 34 is disposed somewhat in advance of the front wall of the casing 30 and in one side of said casing is an opening 37 which establishes communication between the casing 30 and the fan casing 38. A fan 39 of any preferred construction is secured upon the fan shaft within the casing 38 and in operation creates a blast downwardly through the slots 11 and 65 the casing 30 so that the leaves will be held

to the slots 11 in position to be easily engaged by the stripper blades and effectually severed. The rotation of the blades coacting with the suction created by the fan carries the leaves through the slots 11 and delivers them into the fan casing whence they are discharged through an outlet pipe or stack 40 leading tangentially from the fan casing, as shown clearly in Fig. 2.

It is thought the operation of the machine 75 will be evident from what has been said. The stalks are delivered upon the table 6 in front of the feeding rollers 9 and 10 and are presented to said rollers with their larger ends foremost. The stalks are arranged so 80 that one stalk will pass between each two adjacent pins 25 and will be gripped by and between the feed rollers and drawn forward to the stripper. As the travel of the stalks over the table continues, the stripper blades 85 will be brought successively against the stems of the leaves close to the stalks and will cut through said stems so as to sever the leaves from the stalks. As the feeding of the stalks continues, their ends will pass into 90 the grinding mill and they will then be ground and subsequently treated in the usual manner. It will be readily noted that we have provided a very compact, inexpensive and easily operated machine whereby the 95 stalks may be stripped at the same time that they are ground so that time and labor now required to strip the leaves by hand are saved. Moreover, the quality of the syrup is improved inasmuch as the stalks are not 100 stored after being cut or harvested until some convenient time when they may be ground; but the grinding is effected immediately following the stripping.

Having thus described the invention, what 105 is claimed as new is:

In an apparatus for the purpose set forth, the combination of a table top having a transverse series of longitudinal slots therein and a transverse slot in advance of the 110 longitudinal slots, a transverse series of rigid pins rising from the table top adjacent and in advance of the transverse slot and alined with the respective longitudinal slots, co-operating upper and lower feeding rollers 115 mounted respectively above and below the table top in the vertical plane of the transverse slot, a rotatable stripper mounted below the table top, blades carried by said stripper playing through the longitudinal 120 slots in the table top, a hood secured upon the table top and housing the blades, the front and rear ends of said hood being open and the rear end contracted, and means for operating the stripper and the feed rollers. 125

In testimony whereof we affix our signatures.
